UNITED STATES PATENT OFFICE.

HERMAN R. KOESTER, OF CINCINNATI, OHIO, ASSIGNOR TO THE PHILIP CAREY MANUFACTURING COMPANY, A CORPORATION OF OHIO.

HEAT-INSULATING TABLE MAT.

Application filed June 14, 1919. Serial No. 304,111.

To all whom it may concern:

Be it known that I, HERMAN R. KOESTER, a citizen of United States, and a resident of Cincinnati, in the county of Hamilton, 5 State of Ohio (whose post-office address is Chase and Badgeley Avenues, Cincinnati, Ohio), have invented a new and useful Improvement in Heat-Insulating Table Mats, of which the following is a specification.

10 My invention relates to heat insulating table covers, mats, etc., particularly adapted to prevent the heat radiation from dishes or other utensils whereby damage is caused to the table, particularly if it is a highly 15 polished surface. It more especially relates to such mats made in several parts connected by hinges to conform to the size and shape of a table. I have sought to provide a table mat which is heat insulating and 20 fire resistant, has a substantially uniform even flexible, elastic, sound deadening surface, affording a comparatively soft surface for the dishes to be placed upon to protect them from breakage. I also provide 25 exterior covers for the table mat which may be readily removable if desired for cleaning.

In the drawings like characters represent like parts. Fig. 1 is a top view of a half 30 section of a mat formed of three parts. Fig. 2 is an end view of Fig. 1. Fig. 3 is a top view of the mat with the cover removed. Fig. 4 is an end view of Fig. 3 showing a portion of the cover in position. 35 In the drawings I have shown one half of a mat arranged for a round table. A is the cover material of the mat which may be of canton flannel or any suitable material, if desired, a soft material on one side 40 such as canton flannel, etc., and on the reverse side a waterproof material such as oil cloth, etc. B, B, are plies of wool felt, felted paper or similar suitable soft, flexible, elastic, heat insulating material. C is 45 a ply of asbestos paper or suitable fire resistant material which is indented, pitted or provided with numerous small openings so arranged as to provide, when C is placed against the ply B or between two plies B, B, 50 a multiplicity of small air spaces D as non-conductors of heat. The plies A, B and C are held in fixed relation to each other preferably by stitching E although any other

suitable means could be used. The stitching E passes around the portion, of each 55 section of the mat, forming the circumference or periphery of the complete mat and near or along the adjacent edges of two sections of the mat, as clearly shown in Fig. 3 where I, I, represent spaces between different sections of the mat. The different sections of the mat are attached to either by 60 hinges F made preferably of fabric strip material and cemented by suitable adhesive to the adjacent portion of two sections as 65 shown in Figs. 3 and 4 to form a suitable hinge. I prefer, so as to make the mat easily foldable to arrange the fabric hinges on opposite sides so that one portion of the mat may be folded on one face of a central 70 portion and another portion may be folded on the opposite face of the same portion. As shown in Fig. 4 the extreme left portion is arranged to be folded on top of the central portion while the extreme right portion 75 is folded on the opposite side of the central portion. I prefer as shown in the drawings to have the hinges F extend over the adjacent sections a sufficient distance so that they extend beyond the point where the line 80 of stitching E is located, thereby giving increased strength along adjacent parts of different sections as the tendency of the stitching may sometimes be to weaken same. Having attached the plies together I then 85 place the cover of canton flannel, waterproof material or both or other suitable material, one on each side, and the other over the assembled parts of the mat shown in Fig. 3. This cover A may be fixed to 90 one or both of the plies B by suitable adhesive material H, if desired, but I prefer in most cases to omit the adhesive material H so that the cover may be readily removed by the user for the purpose of cleaning 95 same. After the cover is in place on the assembled portion of the mat shown in Fig. 3, I provide a row of stitching J penetrating the cover of all the plies B and C so as to retain said cover in position. If the 100 cover is to be removed the stitching J is opened and the cover removed, cleaned and replaced after which the stitching J is replaced to hold the cover in position. Of course if desired the stitching J may be 105 arranged so that it will not penetrate the

assembled plies, or snap buttons could be used to engage and hold the cover portions together.

What I claim is—

- 5 1. A table mat composed of a plurality of separate independent parts adapted to be folded upon each other, each of said parts comprising a plurality of plies, one of said plies being an asbestos sheet, two 10 other independent plies of flexible elastic heat insulating and sound deadening material, one arranged on each side of said asbestos sheet, said asbestos sheets having a plurality of indentations forming separate independent air spaces enclosed by said asbestos ply and said adjacent plies, rows 15 of stitching attaching said plies in fixed relation to each other, a hinge attaching said separate independent parts of said mat to

gether, formed of a flat flexible material 20 overlaying a substantial portion of the adjacent parts of said mat, and extending inward on said parts beyond the lines of stitching holding the said plies of material together.

25 2. A table mat comprising a plurality of plies, one of said plies being an asbestos sheet, two other independent plies of flexible elastic heat insulating and sound deadening material, one arranged on each side of said fire resistant ply, said asbestos sheet having a plurality of indentations forming a plurality of separate independent air spaces enclosed by said asbestos ply and said adjacent plies.

30 In testimony whereof, I have signed my name to this specification.

HERMAN R. KOESTER.
